UNITED STATES PATENT OFFICE.

WILLIAM S. HIGHT, OF BUCYRUS, OHIO, ASSIGNOR TO THE FREY-SHECKLER COMPANY, OF SAME PLACE.

BRICK OR TILE MACHINE.

SPECIFICATION forming part of Letters Patent No. 504,781, dated September 12, 1893.

Application filed April 1, 1893. Serial No. 468,707. (No model.)

To all whom it may concern:

Be it known that I, WILLIAM S. HIGHT, a citizen of the United States, residing at Bucyrus, in the county of Crawford and State of Ohio, have invented certain new and useful Improvements in Brick or Tile Machines; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

15 Figure 1, is a perspective view of a brick machine embodying my invention. Fig. 2, is an enlarged sectional view of the outer ends of the concentric screw shafts, the flanged bushing interposed between the two, the bushing or bearing for the outer shaft, the cap plate, and the screws for holding the shafts centrally. Fig. 3, is a sectional view of the bushing with its vertically disposed flange for preventing the material working its way between the concentric shafts. Fig. 4, is a sectional view of the bushing or bearing showing its annular groove for the reception of Babbitt-metal or other packing. Fig. 5, is a face view of the box in which the shafts are mounted. Fig. 6, is a face view of the cap plate. Fig. 7, is a sectional view of the same.

20 My invention relates to that class of brick or tile making machines which first grind or pulverize the clay, then force it through a die by means of revolving beaters or screws and, as the clay emerges from the outlet of the machine or die, deliver it upon a table where it is cut into sections or blocks of the shape and approximate size of a brick or tile.

25 In carrying out my invention I prefer to use the form of machine shown in Fig. 1, although it is perfectly evident that my improvements may be applied to other well known forms of machines of the class before mentioned.

30 In machines of this character serious trouble has been often occasioned by the clay being forced or working its way between the concentric screw shafts or between the bushings usually placed between the adjoining faces of said shafts and becoming hard and dry, not

only greatly retarding the free working of the machine, but also finally wearing away the shafts or bushings to such an extent that their removal became a necessity and new ones 55 were often required. This greatly increased the running cost of said machines and required frequent stoppages for adjustment and repairs.

35 The essential object of my invention is to overcome these defects, and to provide a simple and comparatively inexpensive means for preventing the clay finding its way between the shafts or between the bushings therein.

40 Referring now to the accompanying drawings for a more complete explanation of my invention, A represents a cylinder or casing supported upon a suitable bed or frame in which the power shaft B is mounted and provided with a pulley C to which power may be 45 applied in any well known manner, the said pulley having a frictional or other brake D of any well known form and construction, and said shaft having mounted upon it a pinion E and gear wheel F as shown in Fig. 1; said pinion meshing with a gear b on a counter-shaft H which also carries a pinion I which meshes with and drives a large gear J on the hollow screw shaft K, and said gear F meshing with and driving a gear L on a shaft M 50 placed within the hollow shaft.

45 The cylinder or casing of the machine has at its outer or discharge end a flange a to which a similar flange b on the die A' is bolted as shown. Upon the hollow shaft a propeller 55 c with blades or wings is placed and adapted to disintegrate the material and feed it toward the outlet or die, and upon the inner shaft M, is a propeller c' operating with the propeller of the hollow shaft but in an opposite direction and geared so as to run at a higher speed than the first named gear.

50 The machine is also provided with a feed hopper N and as far as described represents a form of brick or tile machine now extensively in use. It is to this preferred form of machine that I apply my present improvements, and to make these more manifest I will now refer to the detailed figures of the drawings.

55 In Fig. 2, a solid box or head 10 is adapted to be fitted within the cylinder or casing just

back of the flanges *a* and *b*, and it is suspended in place by screws 11 preferably three in number placed equidistant around it, with their shanks extending through the inner chamber 5 of the casing or cylinder to the outside thereof whereby they may be adjusted without any derangement of the machine. The purpose of these screws and the head 10, is to always maintain the operating propeller shafts in the 10 central plane of the casing, and to facilitate this result the inner threaded ends of the screws pass into threaded openings in the head or box 10 as shown. The center of the box or head 10 is adapted to receive the outer 15 end of the hollow propeller shaft, said shaft being internally bored to receive a cast iron or other bushing 12 which fits it snugly and has itself a long internal groove 13 adapted to receive Babbitt metal or any other suitable 20 packing for the purpose of making a close bearing with the other propeller shaft or a bushing thereon.

Through the hollow shaft K passes the shaft M which projects beyond the end of the first 25 named shaft and has the propeller fitted to it. This internal shaft is concentric with the hollow shaft and is provided with a bushing 14 of malleable iron or other appropriate material, and is fitted snugly to the shaft and 30 revolves therewith with its inner end abutting against the end wall of the bore formed in the interior of the hollow shaft. This bushing 14 is formed or provided with a deep annular flange 15 vertically disposed when 35 the parts are in position, and has one of its side faces adapted to be closely fitted against the outer ends of the hollow shaft and its bushing to form a close joint at this point, and having its opposite side face adapted to 40 fit within an annular recess formed in the in-

ner face of a cap plate 16 shown in Figs. 2, and 7, adapted to be securely held in place by means of bolts or screws 17 passing through it and into the box or head 10 as shown in Fig. 2. By this forming the flange 15 upon 45 the bushing carried by the inner screw shaft, the outer ends of the bushing 12 and hollow shaft are securely closed against the admission of clay between these parts thereby overcoming the difficulties incident to the clay 50 being forced back by the resistance of the propellers and finding its way into the crevices between the bearing surfaces, as before pointed out.

Having thus described my invention, what 55 I claim as new, and desire to secure by Letters Patent, is—

1. In brick and tile machines having a chamber or cylinder in which the clay is mixed, a hollow shaft carrying a propeller, a 60 shaft within the hollow shaft, and a vertically disposed flange carried by the inner shaft and adapted to rest against the end of the hollow shaft to prevent the admission of clay between the shafts. 65

2. In brick and tile machines having a chamber or cylinder, in which the clay is mixed, a hollow propeller shaft having an inner bore at its outer end, a shaft within the hollow shaft having a bushing provided with a 70 vertical flange adapted to bear against the end of the hollow shaft and its bushing to close the joint and prevent the admission of clay between said shafts.

In testimony whereof I affix my signature in 75 presence of two witnesses.

WILLIAM S. HIGHT.
